(57) **CLAIM**

The ornamental design for an infusion pump, as shown and described.

DESCRIPTION

FIG. 1 is a perspective view of an infusion pump with its cover in a closed position;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is another perspective view of the infusion pump with its cover in an open position; and,

FIG. 8 is a front view thereof.

The broken lines in the figures depict portions of the infusion pump that form no part of the claimed design.

1 Claim, 6 Drawing Sheets
